UNITED STATES PATENT OFFICE.

CHARLES F. SMITH, OF NEW BRITAIN, CONNECTICUT, ASSIGNOR TO THE LANDERS, FRARY & CLARK, OF SAME PLACE.

DESIGN FOR A FERRULE.

SPECIFICATION forming part of Design No. 33,817, dated January 1, 1901.

Application filed December 5, 1900. Serial No. 33,842. Term of patent 7 years.

To all whom it may concern:

Be it known that I, CHARLES F. SMITH, a citizen of the United States, residing at New Britain, in the county of Hartford and State 5 of Connecticut, have invented and produced a new and original Design for a Ferrule, of which the following is a specification, reference being had to the accompanying drawing, forming part thereof.

10 The only figure is a side elevation of a ferrule, showing my new design.

As shown in the drawing, the sides of the ferrule are plain for a short distance at each end and then provided with the rounded bead

15 2. Extending inwardly each way from these beads 2 the ferrule is encircled by an orna-

ment composed of conventional leaves 3 and flowers 4, grouped together and resting on the beads 2 as a base, all as shown. The middle portion between the ornaments is plain. In 20 end view the ferrule is of an ordinary oval form.

Having described my invention, what I claim as new, and desire to secure by Letters Patent, is—

25 The design for a ferrule, as herein shown and described.

CHARLES F. SMITH.
